DESIGN FOR A COMBINATION RECORDING BOOTH AND PHOTO STUDIO

Donald Bruce Phillips, New York, N. Y.

Application April 13, 1945, Serial No. 118,982

Term of patent 7 years

(Cl. D61—1)

To all whom it may concern:

Be it known that I, Donald Bruce Phillips, a citizen of the United States, residing at New York city, in the county of New York and State of New York, have invented a new, original, and ornamental Design for a Combination Recording Booth and Photo Studio, of which the following is a specification, reference being had to the accompanying drawing, forming part thereof.

The drawing shows a perspective view of a

combination recording booth and photo studio, showing my new design.

The back and opposite side of the booth (not shown) are plain.

I claim:

The ornamental design for a combination recording booth and photo studio, substantially as shown and described.

DONALD BRUCE PHILLIPS.
